US00D673161S

(12) **United States Design Patent**
Kuehn et al.

(10) **Patent No.:** **US D673,161 S**
(45) **Date of Patent:** **** Dec. 25, 2012**

(54) **PERFORATION PATTERN FOR A COVER PLATE FOR A COMPUTING DEVICE**

(75) Inventors: **Keith J. Kuehn**, Magnolia, TX (US);
Brooks Vaughan, Tomball, TX (US)

(73) Assignee: **Hewlett-Packard Development Company, L.P.**, Houston, TX (US)

(**) Term: **14 Years**

(21) Appl. No.: **29/404,003**

(22) Filed: **Oct. 13, 2011**

(51) LOC (9) Cl. **14-02**

(52) U.S. Cl. **D14/441**

(58) Field of Classification D14/441-446,
D14/313, 349, 356, 360-368; D13/162,
D13/184, 199; 312/223.2; 360/99.01-99.12;
361/679.31-679.33, 679.55; 369/34.01,
369/36.01

(57) **CLAIM**

The ornamental design for a perforation pattern for a cover plate for a computing device, as shown and described.

DESCRIPTION

FIG. 1 is a front view of a perforation pattern for a cover plate for a computing device;

FIG. 2 is a front perspective view of the perforation pattern for a cover plate for a computing device in use on a computing device;

FIG. 3 is a front perspective view of the perforation pattern for a cover plate for a computing device in use on another computing device; and,

FIG. 4 is a front perspective view of the perforation pattern for a cover plate for a computing device in use on another computing device.

The broken lines showing of various regions and the unshaded areas therein are for the purpose of illustrating the article and form no part of the claimed design.

1 Claim, 4 Drawing Sheets

FIG. 1

FIG. 2

FIG. 3

FIG. 4
